UNITED STATES PATENT OFFICE.

WILLIAM A. KERFOOT, OF EVANSTON, ILLINOIS.

PUMP.

SPECIFICATION forming part of Letters Patent No. 723,394, dated March 24, 1903.

Application filed January 20, 1902. Serial No. 90,417. (No model.)

To all whom it may concern:

Be it known that I, WILLIAM A. KERFOOT, of Evanston, in the county of Cook and State of Illinois, have invented certain new and useful Improvements in Pumps; and I hereby declare that the following is a full, clear, and exact description thereof, reference being had to the accompanying drawings, which form part of this specification.

10 My invention relates to improvements in pumps. It has especial reference to a means for controlling the motive power which is used to operate such pumps.

15 The object of my invention is to provide an especially-improved means whereby the motive power of a pump, such as a windmill or the like, may be automatically set into operation or thrown out of operation with reference to the pump by means of an improved automatically-operated device the function of which is brought into effect by the instrumentality of the pump.

20 Whenever a pump is operated by some mechanical power, such as windmills, for filling a receptacle, such as a water tank or reservoir, it is desirable when the said receptacle is filled to stop the motion of the apparatus that supplies the power for operating the pump either as a matter of economy or to save 25 the wear and tear upon the said pump and the motive apparatus. My device is especially adapted to be used with pumps of this class when such pumps are provided with a source of power, such as windmills. It comprises a means whereby the movement of the windmill may be arrested with reference to the pump at predetermined times—such, for instance, as when a tank or reservoir is properly filled with water and it consequently becomes desirable to stop the operation of the 30 windmill and pump.

35 The object of my present invention is to provide an improved construction in the several parts or features of pump-controllers of the character referred to; and it consists in the matter hereinafter set forth, and particularly pointed out in the appended claims.

40 The pump shown in this instance as embodying my invention in one form is a double-acting force-pump of that type in which two cylinders of different diameters are connected with each other so as to be in open

communication at their adjacent ends, with the larger cylinder below and connected with the water-supply by a suitable conduit at its 55 lower end, and in which large and small pistons are attached to a common piston-rod and the larger piston is provided with valve-passages, closing when the pistons are raised and opening when the pistons are lowered, so that 60 on the upstroke of the piston a discharge of water will take place through an outlet provided between the two cylinders equal to the difference in displacement of the large and small pistons, while on the downstroke of the 65 piston an additional discharge equal to the displacement of the small piston will occur.

70 The improved mechanism shown in this specification is adapted to be used in connection with either class of windmills where it becomes necessary to push up on a rod for the purpose of disconnecting the motive power with reference to the pump or in such mills where it becomes necessary to pull down on a connecting rod or chain for the purpose of disconnecting the motive power of the windmill, the arrangement being such that the device may be applied conveniently to either class of mills, and to this especial feature my 75 invention relates.

80 In the drawings, Figure 1 is a sectional elevation of a pump equipped with my controlling mechanism, showing portions of the water-chamber, cylinders, and regulator in section in the plane indicated by the straight 85 section-indicating line 11 of Fig. 3 and portions of the discharge-pipe and its connection with the water-chamber in section on the plane indicated by the angular branch of line 11 in Fig. 3. Fig. 2 is a broken-away 90 portion of the pump, showing the fulcrum and lever of my controlling mechanism reversed in position with reference to that shown in Fig. 1. Fig. 3 is a transverse section taken just above the water-chamber 95 shown in Fig. 1.

95 In Fig. 1 the stop or controlling mechanism is shown as it would be applied to a windmill, whereby the motive power of the mill may become unshipped or disconnected 100 with reference to the pump by pulling down the chain.

In Fig. 2 the mechanism is reversed, and it indicates a means whereby the windmill mo-

tive mechanism may be unshipped or disconnected by pushing up upon the rod.

The mechanism embodying my invention may be applied to any ordinary force-pump. 5 I have shown such a pump in the drawings to which my mechanism is so applied and will describe such a pump in connection therewith.

In the drawings, 1 is the water-chamber of 10 the pump, to which the cylinders 2 and 3 are joined in axial line and which are provided with the usual pistons 4 and 5. A piston-rod 6 may be extended to any power-producing device—such as a windmill, water-wheel, 15 steam-engine, or the like—by which it may be thereby reciprocated. An air-chamber 7 is mounted on and connected with the water-chamber 1. The discharge-pipe 10 is connected with the water-chamber 1, the lower end of 20 which forms a seat for the valve 18. Connected axially in line with the pipe 10 is a nipple 12, the upper surface of which forms a valve-seat. The lower end of the nipple 12 is connected to a conduit-pipe 13, which 25 is led off some distance from the pump to a reservoir. On the upper end of the pipe 13 a float-valve 15 is attached to the lever 15^a, which is pivotally supported upon the bracket 15^b and which is adapted to be opened by the 30 float-weight 16 when the water in the reservoir is below a certain determined point and which is closed by the said float when the water rises to the point shown in the drawings. A valve-rod 17 passes axially through the discharge-pipe 10 and is provided upon its 35 lower end with an adjustable valve 18, shown in the drawings seated on the valve-seat formed by the upper surface of the nipple 12. When the valve is in this position, the 40 pump will discharge through the pipe 10. When the valve is raised and seated upon the lower end of the pipe 10, the pump will discharge through the conduit-pipe 13 into the reservoir 14.

45 20 is a cylinder of my improved device, which is connected to the water-chamber 1 by means of the pipe 21. This pipe is screwed into the removable flange or plate 22, which is held onto the perforated face of the chamber 1 by means of cap-screws 23 23. By this means the entire apparatus may be readily removed from the chamber 1, and when it is desirable to use the pump without my improved device an imperforate plate may be 50 made to take the place of the plate 22 for the purpose of closing the aperture in the wall of the chamber 1.

55 24 is a clamp by means of which and a set-screw 24^a the cylinder 20 is supported in a vertical position by the connection of the clamp 24 with the vertical pipe 7.

25 is a cap which is adapted to be rotated on and afterwards fixed to the upper end of the cylinder 20 by means of set-screws 26 26 60 or by any other convenient and suitable means.

27 is an integrally-formed upwardly-ex-

tending support, and 29 is a guide or stuffing-box through which the piston-rod 30 is adapted to pass freely. The lower end of this rod 70 carries a piston 31, which is held normally in the lowermost part of the cylinder by means of a weight 38 and the open helical spring 32, which is contained within the said cylinder between the cap 25 and the top of the 75 said piston. The upper part 33 of the piston-rod 30 is flattened and carries two grooved rollers 34 and 35, through or between which the arm 36 is adapted to pass. A series of holes 37 are made in the arm 36, and 38 is a 80 weight adapted to be adjusted at varying positions along the arm or lever 36.

39 is a quadrant fixed to the outwardly-extending end of the arm 36, around which the chain 40 is partially wound when a chain is to 85 be used; but a rod may be connected directly to the lever, as shown in Fig. 2. This chain is designed to extend to the windmill or other power-producing device and is arranged to unship or disconnect the power with reference to the pump when the chain or rod is pulled down, as in the operation of the device shown in Fig. 2.

The lever 36 is provided with a slot 28, through which the pin 41 of the support 27 95 passes. The lever 36 is adapted to slide longitudinally when it is being vertically moved by the piston-rod 30 by virtue of the slot 28 and the pin 41, so as to prevent clamping and distortion of the position of the vertically-moving piston-rod.

In Fig. 2 the cap 25 of the cylinder 20 has been rotated one-half of a revolution and fixed and the end of the arm 36, carrying the weight 38, is shown to have been transposed 105 in its position with the end carrying the quadrant 39. In Fig. 2 a push-rod 42 is connected to the end of the lever 36.

43 is a platform, below and to which the pump and the apparatus just described are 110 properly suspended.

The operation of the device is as follows: When the valve 18 is seated upon the lower end of the pipe 10, the water, by the reciprocation of the pistons 4 and 5, is forced through 115 the pipe 13 into the reservoir 14. When the reservoir has been filled, as shown in Fig. 1, the float 16 is raised thereby and the valve 15 is closed. The water will then be forced through the pipe 21 into the cylinder 20, under the piston 31, and will raise the piston against the tension of the spring 32 and weight 38, and thereby raise the outer end of the fulcrum-lever 36 and lower the opposite end of the said lever, which is pivoted at 125 41 on the support 27, and the quadrant 39 will pull down or wind up the chain to some extent, and thereby pull out the shifting device of the windmill and disconnect the operating part from the piston-rod 6. Such an arrangement as shown in Fig. 1 is desirable when it becomes necessary to pull down a rod or the chain 40 in order to unship or disconnect the connecting mechanism.

When a mill is of the character known as a "push-mill"—that is to say, where it is necessary to push upon the rod in order to disconnect it or unship it—then the cap 25 may 5 be revolved or rotated one-half of a revolution upon the top of the cylinder 20 and held in position by the screws, and the connection to such a rod may be made as shown in Fig. 2, thereby shifting the positions of the lever 10 and the fulcrum-support. It therefore will be seen that my device is applicable to both or either types of windmills—a push-up or a pull-down mill—it being only necessary to revolve the cap 25 one-half of a revolution to 15 use either end of the fulcrum-lever 36 and for transposing the position of the fulcrum-support for the purpose of pulling down or raising up the shifting rod when piston 31 is raised in the cylinder 20.

20 The weight 38 may be used as a means for adjusting or for more finely graduating the tension of the device than can be produced by the spring 32 when used alone. This weight will be properly placed whether the 25 device is in the position shown in Fig. 1 or in Fig. 2, as it sometimes becomes necessary to increase the pressure in the cylinder 20, which is essential for raising the piston 31 for the purpose of overcoming resistance 30 in the pipes, so that there will be sufficient tension in the spring 32 or an equal effect produced by the weight 38 for the purpose of forcing the water contained in the cylinder 20 into the reservoir 14 whenever the valve 15 35 is raised, and thereby opening the outlet in the pipe 13, so that the cylinder 20 will become completely discharged.

Having described my invention, what I claim as new and useful, and desire to secure 40 by Letters Patent of the United States, is—

45 1. In combination with a pump, of a source of power for actuating said pump connected therewith, and a power-controlling device comprising a cylinder, a piston in said cylinder, a cap adapted to be rotated on and secured to said cylinder, a support carried by and located on one side of said cap, a lever fulcrumed on said support, a piston-rod con-

necting said piston and said lever, a means for depressing said piston, a connection between said source of power and said controlling device, and a means for connecting said connection to either end of said lever, by rotating the cap upon said cylinder and thereby changing the positions of the fulcrum for 50 the lever and the ends of said lever.

2. In a power-controlling device for a pump, the combination of the cylinder 20, a rotatable cap 25 adjustably secured thereto, a support 27 fixed on one side of said cap, a piston 60 31 within the casing, a piston-rod 30, and an operating-lever 36 fulcrumed on the support 27 and loosely connected with the piston-rod 30, said lever extending beyond said rod and support in both directions and provided at 65 each end with means for attachment to the pump-connecting instrumentalities.

3. In a power-controlling device for a pump the combination, of a cylinder 20, the cap 25 adapted to be rotated thereon, set-screws 26 70 for fixing the cap in position, the support 27 on one side and integral with the said cap, the lever 36 fulcrumed to said support, the piston 31, the piston-rod 30 adapted to raise and lower said lever, and an open helical 75 spring 32 between said cap and said piston for depressing said piston.

4. In a power-controlling device for a pump the combination, of a cylinder 20, a lever 36, pivoted on a fulcrum-support 27, a piston-rod 80 30 for moving said lever, and grooved wheels 34 and 35 carried by said piston-rod between which said lever passes.

5. In a power-controlling device for a pump the combination, of a cylinder 20, a lever 36, 85 pivoted on a fulcrum-support 27, a piston-rod 30 for moving said lever, grooved wheels 34 and 35 between which said lever passes, and a slot 28 in said lever.

In testimony that I claim the foregoing as 90 my own I affix my signature in presence of two witnesses.

WILLIAM A. KERFOOT.
